UNITED STATES PATENT OFFICE.

EDWARD R. CARPENTER, OF GRAND RAPIDS, MICHIGAN.

GOLF CLUB.

Application filed October 16, 1922. Serial No. 594,734.

To all whom it may concern:

Be it known that I, EDWARD R. CARPENTER, a citizen of the United States, residing at Grand Rapids, in the county of Kent and State of Michigan, have invented new and useful Improvements in Golf Clubs, of which the following is a specification.

The present invention relates to golf clubs, i. e., the instruments employed in the game of golf to drive or propel the balls; and its object is to provide such an instrument having a handle portion and a body portion provided with means for readily adjusting the weight of the body portion as may be desired by the individual player.

This object is attained by, and the invention finds preferable embodiment in, the instrument particularly described in the body of this specification and illustrated by the accompanying drawings, in which:

Figure 1 is a view of a golf club or golf stick looking toward the front edge of the body portion thereof, said body portion being partially sectioned on a vertical plane corresponding to line 1—1 of Figure 2;

Figure 2 is a top plan view of said body portion, its neck being broken away; and

Figure 3 is a transverse sectional view of said body portion taken on line 3—3 of Figure 1.

In the views, a "golf club" or "golf stick" is shown, having a handle portion designated generally 1 and a body portion 2 where-with the golf ball is struck to drive or propel the same. This body portion is preferably made of some light and stiff material as aluminum and has a neck 3 extending inclinedly-upwardly therefrom as seen in Figure 1. This body portion and its neck are hollow throughout, being a shell inclosing a chamber 4 which extends continuously through the neck to a port 5 at the neck's outer extremity. This port is closable, preferably by the handle portion 1 itself, which

extends in the direction of the neck and is 45 provided at its lower end with suitable means for detachable connection with the hollow neck to close the same and the chamber in the body portion. Such means is preferably the threaded lower end 6 of the ferrule 7 whose 50 socket 8 receives the lower end of the shaft 9 of the handle portion, said threaded end turning in the nut portion 10 of the neck. A suitable washer 11 may be provided as shown in Figure 1 as a packing for the joint 55 between the ferrule and the neck.

Suitable weights 12, as gravel, lead shot and the like, are introduced through the hollow neck into the chamber 4 to supply the additional weight desired by the player, 60 and a suitable packing material 13, lighter than the weights, as cotton waste and the like, may be likewise thus introduced to hold the weights tightly in place in the chamber. It will be readily understood that the weight 65 of the golf club and particularly of its body portion may be easily adjusted to suit the individual liking of the user of the instrument.

The invention, being intended to be pointed out in the claims, is not to be limited to or by details of construction of the particular embodiment thereof illustrated by the drawings or hereinbefore shown or described.

I claim:

In a golf club; a body portion having a neck inclined relatively thereto, and a chamber extending through the neck; an elongated handle portion extending in the direction of the neck and adapted to be detachably connected thereto to close the chamber; weights and packing material in the chamber adapted to pass thereinto and therefrom through the neck.

In testimony whereof I have hereunto set 85 my hand at Grand Rapids, Michigan, this 13th day of October, 1922.

EDWARD R. CARPENTER.
